Specification for Design.

Patented Oct. 16, 1917.

Application filed August 17, 1917. Serial No. 186,808. Term of patent 8½ years.

To all whom it may concern:

Be it known that I, FREDERIC W. EICHORN, a citizen of the United States, residing at Chicago, in the county of Cook and State of Illinois, have invented a new, original, and ornamental Design for a Vanity-Case, of which the following is a specification, reference being had to the accompanying drawing, forming a part thereof, wherein—

Fig. 2 is a side view, and

Fig. 3 is a rear elevation of a vanity case, showing my new design.

I claim as my invention:

The ornamental design for a vanity case, as shown.

FREDERIC W. EICHORN.
